Rudolph Wendt of New York City

Letters Patent No 9172, Dated Sept 2, 1875

Design for a Spoon Handle

The schedule referred to in these Letters Patent and making part of the same.

To all whom it may concern:

Be it known that I, Rudolph Wendt of the City, County and State of New York have invented a new and ornamental Design of Spoon Handle and I do hereby declare that the following is a full, clear and exact description thereof which will enable others skilled in the art to make and use the same reference being had to the accompanying drawing forming part of this specification in which:

Figure 1, represents a front elevation of this invention.

Figure 2, is a rear elevation of the same.

Similar letters of reference indicate like parts.

This invention relates to a design on the upper and on the under surface of the spoon handle. The upper surface is ornamented by three fine raised lines extending downward near to the junction of the handle with the bowl where they cross each other and entwine three times. Said lines extend on the sides of the shank or thin part of the handle and they cross each other again forming a pointed oval and finally they are entwined on both sides of the handle and turn back under the pointed oval where they disappear.

The points of the oval are ornamented by buttons and the oval itself bears the figure of a female representing one of the nine muses. The extreme end of the handle spreads and is ornamented by a series of leaves.

2

On the under surface of the handle is ornamented by three lines forming the contours of the shank and with a pointed oval similar to those on the top and the wide part on the extreme end of the handle is also ornamented on the under side by leaves and lines similar to those on the upper surface. The junction of the handle with the spoon is ornamented by a raised semi-circular band from which emanate a bunch of leaves.

A represents the top of the handle the contour of which is formed by three fine raised lines a, which extend down near to the junction of the handle with the bowl. These lines cross at b, and they are entwined at three different places as shown at c. The space between these lines forms a semi-circular groove d. And said lines run up near the edge of the shank of the handle, and cross again at e, forming the contour of the pointed oval f. After having formed said oval the three lines are entwined again on both sides of the handle at g where they turn down and disappear under the oval f. The points of the oval are ornamented by buttons and the oval itself is occupied by a human figure h representing Lepichore or one of the nine muses.

The extreme upper end i. of the handle spreads and is ornamented by a series of leaves j.

The under surface C of the handle is ornamented in a similar manner to the upper surface by three lines forming the contours of the shank and of the pointed oval. The broad extreme end being also ornamented by leaves on the under as well as on the upper surface.

3

At the junction of the handle with the bowl the under surface of the handle is ornamented by a segmental band from which emanate a bunch of leaves, said band being connected to the extrined ends of the three lines by an arabesque.

By these means a spoon handle is produced which presents a new and original design.

I claim as new and desire to secure by Letters Patent The design for a spoon handle as shown and described.
